UNITED STATES PATENT OFFICE.

FREDERIC WILLIAM BARTHMAN, JR., OF BROOKLYN, NEW YORK.

DESIGN FOR A BOX.

SPECIFICATION forming part of Design No. 23,445, dated July 10, 1894.

Application filed May 10, 1894. Serial No. 510,801. Term of patent 7 years.

To all whom it may concern:

Be it known that I, FREDERIC WILLIAM BARTHMAN, Jr., a citizen of the United States, residing at Brooklyn, Kings county, State of New York, have invented and produced a new and original Design for a Box, of which the following is a specification.

In the accompanying drawings forming part of this specification—Figure 1 is a perspective view of a box, illustrating my design. Fig. 2 is a central vertical section showing the cover of the box. Fig. 3 is a longitudinal section of the box showing the cover removed therefrom.

The characteristic features of my design consist in a box having the formation of a cap and wherein a roughened band extends almost the entire height of the crown, over which roughened band projects, at a sharp angle, the top of the crown which constitutes

the cover of the box and the lower edge thereof having the bottom of the box connected thereto.

In the drawings A represents a roughened band extending almost the entire height of the crown of the cap which forms the body of the box. At the lower edge of this roughened band is connected the bottom x of the box, from which also projects the peak B. Projecting outwardly at a sharp angle from the top of the roughened band A is the top C of the cap which constitutes the cover of the box.

What I claim is—

The design for a box, substantially as shown and described.

FREDERIC WILLIAM BARTHMAN, JR.
